ANTENNA

John Evans, Riverside, N. J., assignor to Radio Corporation of America, a corporation of Delaware

Application April 28, 1934, Serial No. 722,837

10 Claims. (Cl. 250—33)

This invention relates to antennas and more particularly to a device of that class in which short-wave radio frequency energy may be transmitted or collected.

5 In certain instances it is desirable that the radiant energy be propagated into space from a point of rather high elevation and considerably removed from the transmitting apparatus. In order that the transmission line interconnecting the transmitter and the radiating antenna shall be of such construction as to minimize the energy losses therein, I have evolved a means suitable for this purpose which has many advantages, including those of simplicity, 10 low cost of installation, and low upkeep cost.

Accordingly, it is an object of my invention to provide an antenna system in which the energy radiating or collecting element thereof is located at a considerable height above ground while the radio apparatus may be located near the ground.

20 Another object of my invention is to provide a supporting structure for a transmitting or receiving antenna which has sufficient strength and durability to make it advantageous over other forms of antenna structure.

25 Another object of my invention is to so connect a transmitting apparatus with the radiating portion of an antenna system as to minimize the attenuation of signals transmitted.

30 The novel features considered characteristic of my invention are set forth with particularity in the appended claims. The invention in its entirety, however, both as to its organization and its method of operation, together with additional objects and advantages thereof, will best be understood from the following description of 35 a specific embodiment when read in connection with the single figure of the accompanying drawing.

40 It is now well known that in the transmission of intelligence by means of ultra short-wave and quasi-optical radio frequencies it is highly advantageous that the actual radiator should be of sufficient height above the earth's surface so 45 that the emitted signals shall not be tangential thereto except outside the range of reception of such signals. Going quite contrary to the generally accepted practice, I have found that very satisfactory results may be obtained by 50 mounting the radiating portion of my antenna system at the top of a metal pole and coaxial therewith. Such a radiator I have indicated at 55 11 as having a length

or half the length of the wave to be propagated. The antenna pole 12 may be constructed of sections of metal pipe which may or may not be non-ferrous. The pole may be held erect in any suitable manner as by being partly sunk in the ground, or by means of hemp or non-metallic guy ropes, not shown. No insulation is necessary between the radiating portion 11, the pole 12 and ground. It is desirable, however, that the radiator 11 be at least five wave-lengths 10 above the ground or grounded support of the pole so as to minimize distortion of the signals, and also in order that the feeder system 13 may be sufficiently spaced from the ground to avoid phase cancellation.

15 In order to transfer the signalling energy from the transmitter to the radiator 11 without dissipation thereof to ground and also without permitting the pole 12 to become a radiator, I have provided a structure which includes a wire 20 or metallic strip 13 disposed parallel to and insulated from the pole 12. The conductor 13 terminates on a level with the bottom of the radiator 11, but is not connected thereto. It passes through a number of insulators 14 and 25 may be kept taut by means of a weight 15 attached to its lower end. The conductors 19, which are in the output circuit of the transmitter, connect at points 16 and 17 respectively with the metallic pole 12 and with the conductor 30 13. The connections 16 and 17 are made as 35 nearly as possible on the same level.

40 Interposed between the pole 12 and the conductor 13 at a suitable point below the connecting points 16 and 17 I make an electrical 35 connection which may, if desired, include an ammeter A, and preferably a hot-wire instrument of this type. It is essential that this connection between the pole 12 and the conductor 13 be made so that the effective length of the conductor portion a from the connecting point 17 to the electrical center of the ammeter shall be

$\frac{\lambda}{4}$

45

46 and the same effective length shall exist along the pole portion b from the electrical center of the ammeter up to the connecting point 16. The ammeter A serves to locate its own position 50 for optimum results. When the ammeter A shows a maximum reading it will be understood that the section a of the conductor 13 and b of the pole 12 provide an effective insulation of the structure above the feeders with respect to 55

ground and for the particular radio frequency to which the system is tuned.

It will be apparent to those skilled in the art that the portion of the structure above and including the feeders 19 from the radio transmitter constitute an electrically symmetrical and self-neutralizing part of the system, and that a very high percentage of the output energy from the transmitter is thereby transferred to the 10 portion 11, from which it is radiated.

In certain instances the radiator 11 may not be of sufficient length to produce a voltage maximum at its base c. To overcome this difficulty, impedances, either loading coils or series condensers 18, may be inserted in the transmission line from the transmitter to the antenna proper. Condensers are preferable to loading coils because they may be adjusted while the signal strength is being observed on the ammeter A.

20 The advantages to be gained by the very simple structural arrangement of my antenna system will readily appear to those skilled in the art. This disclosure will also suggest modifications of my invention which, however, would not 25 be a departure from the spirit and scope thereof. The applicability of my antenna system to radio reception, as well as to transmission, is also apparent. The particular embodiment shown is, therefore, to be understood as merely an example. 30 Accordingly, I do not intend to be limited to the particular structural details herein described, but only as necessitated by the prior art and by the spirit of the appended claims.

I claim as my invention:

35 1. A metallic antenna pole electrically grounded at its base, in combination with means for rendering an upper portion of said pole radiative and the remaining portion thereof non-radiative, means for impressing signalling energy upon said 40 pole and contraphasally upon the first said means, and means for effectively preventing the dissipation to ground of signalling energy impressed upon said pole, the last said means constituting an electrically conductive path of substantially a half-wave length at the frequency of 45 said signalling energy along portions of the first said means and of said pole, respectively, and including a current responsive device interconnecting said portions.

50 2. The invention set forth in claim 1 in which the radiative portion of said pole is of approximately half the length of the radio frequency wave to be propagated.

3. The invention set forth in claim 1 in which 55 the means for rendering different portions of said pole radiative and non-radiative, respectively, is constituted by a single conductor disposed substantially parallel to and along one side of said pole and approximately coextensive with the 60 non-radiating portion.

4. In combination with a radio transmitter, a 65 substantially vertically disposed metallic antenna pole electrically grounded at its base, means extending substantially parallel to said pole for effectively cancelling the radiating effect except from an upper portion thereof which is of substantially half the length of one of the waves to be transmitted, separate connections from one 70 point on said means and from another point of corresponding height on said pole, both being included in the output circuit of said transmitter, and means interconnecting said pole and the first said means such that a voltage loop is established

thereat for preventing the dissipation of radio frequency energy to ground.

5. An antenna system having a space-energy transfer element of effectively a half-wave length in respect to the signalling frequency for which it is intended, a metallic supporting pole for said transfer element, a conductor disposed parallel to and insulated from said pole, a two-wire transmission circuit connecting a given radio apparatus with said pole and with said parallel-disposed conductor at points substantially equidistant from the ground level, and a conductive loop of effectively a half-wave length, said loop including portions of said pole and of said parallel-disposed conductor extending downwardly from 10 said points of connection with said transmission circuit.

6. An antenna system in accordance with claim 5 and having an ammeter disposed substantially at the point in said loop where an anti-node of 20 current occurs.

7. An antenna system in accordance with claim 5 and having variable impedances disposed in said transmission circuit.

8. A metallic antenna pole electrically grounded at its base in combination with means for effectively preventing the dissipation to ground of signalling energy impressed upon said pole, said means being constituted by a conductor disposed substantially parallel to and coextensive with a portion of said pole below the point whereat the pole receives its energy, and an electrical connection between said pole and said conductor at a point substantially one quarter wave-length removed from points on said conductor and on said pole, respectively, whereon signalling energy is impressed.

9. An antenna system comprising an upright metallic pole the base of which is electrically grounded with respect to stray and transient energy, in combination with a conductor disposed parallel to and along one side of said pole for a distance at least greater than a quarter wave length of signalling energy of a frequency at which said system is intended to be operated, means for establishing a conductive path between a point on said conductor and said pole, means for establishing a potential point in said conductive path which effectively prevents the dissipation of said energy to ground, a source of energy of the desired frequency, and means coupling said source to the nodal current points of said conductive path.

10. An antenna system comprising an upright metallic pole the base of which is electrically grounded with respect to stray and transient energy, while being effectively insulated from ground with respect to signalling energy of a given frequency, in combination with means including a conductor disposed parallel to and along one side of said pole for a distance at least greater than a quarter wave length of said signalling energy said means being such that the opposed portion of said pole is rendered non-radiative of said energy while a portion of said pole extending above the extreme height of said conductor is rendered radiative, a junction between said conductor and said pole, means for establishing at the said junction a potential node with respect to ground, a source of oscillatory signalling energy, and means coupling said source to said pole and conductor at current nodal points.

JOHN EVANS.
